UNITED STATES PATENT OFFICE

EDGAR DE NIO, OF WOODFORD, NEW YORK

SCRAPING AND CLEANING IMPLEMENT

Application filed September 11, 1930, Serial No. 481,244. Renewed September 1, 1932.

This invention relates to an improved tool or implement which is especially, but not necessarily, designed for use in cattle barns and analogous places, and it has more particular reference to a device which is expressly designed to serve as a scraper for removing crustations and accumulated refuse matter from stalls and concrete floors.

The inventive conception comprehends a tool of this class which is characterized primarily by an appropriate handle and a sheet steel blade, of appropriate resiliency to function as a scraping element as well as a shovel, said implement also embodying additional accessories to facilitate cleaning of grooves in concrete floors, as well as cleaning the blade itself of matter deposited thereon.

In the drawing:

Figure 1 is an elevational view of the complete tool constructed in accordance with the present invention.

Figure 2 is a longitudinal sectional view.

Figure 3 is a cross section on the line 3-3 of Figure 1.

In the drawing, the blade is designated by the numerals 4. This is in the form of a rectangular sheet of steel of appropriate strength. It is sufficiently flexible to facilitate scraping and cleaning. This blade is secured by a bolt 5 at its upper end between the furcations 6 of the coupling shank 7. This shank extends into a socket 8 in the connector 9. The threaded end of the bolt is provided with a retaining nut 10.

The element 9 is formed with a screw-threaded socket into which the threaded end of the handle 11 is screwed.

The numeral 12 designates a cleaning rod which is pivoted as at 13 to the upper edge portion of the blade. This rod is formed with a suitable handgrip as at 14 and is of a length to permit it to be swung down to project beyond the scraping edge 15 of the blade for removing and wiping accumulations therefrom.

This arm or rod 12 sweeps entirely across the face of the blade for effective cleansing. The numeral 16 designates what may be re-

ferred to as a raking finger. This has a laterally directed end portion 17 pivoted as at 18 close to the furcation 6, thus allowing these furcations, or at least one of the furcations to function as a stop shoulder when the finger is in the operating position shown in full lines in Figure 1. The finger is of a length to project beyond the scraping edge 15 so as to permit it to be dragged along in grooves in concrete floors and the like for raking accumulated matter from the grooves.

When the finger is not in use, it is swung upwardly to an out-of-the-way position alongside of the handle in an obvious manner. It is frictionally held in the latter position. Thus the raking finger 16 is pivoted on one side of the bolt 5 and the cleaning arm 12 is pivoted on the opposite side. Particular novelty is predicated upon the laterally directed end portion 17 which abuts the adjacent furcation 6 to utilize said furcation as a stop to aid in holding the scraping fingers in operating position.

The method of operation and use of this scraping device together with the advantages developed by the presence of the accessories 12 and 16 is obvious. Persons skilled in the art to which the invention relates will be able to obtain a clear understanding of the construction and advantages by considering the description in connection with the drawing. Therefore, a more lengthy description is regarded as unnecessary.

Minor changes in shape, size, and rearrangement of features coming within the field of invention claimed may be resorted to in actual practice if desired.

I claim:

1. Means for cleaning the blade of a scraper implement comprising an arm pivotally connected to the upper part of the blade whereby said arm can be swung across the blade to clean one face thereof.

2. In combination with a scraper implement including its blade, a bar having one end formed with a right angular extension, the extremity of which is pivoted to one face of the blade adjacent the upper end of the blade and a projection on said face of

the blade with which the bent end of the bar will contact when the bar is in operative position, and having the free end of the bar extending beyond the edge of the blade 5 when the bent end of the arm is in contact with the projection.

In testimony whereof I affix my signature.
EDGAR DE NIO.
